SEPARABLE FASTENER

Noel Joseph Poux, Meadville, Pa., assignor to
 Talon, Inc., Meadville, Pa., a corporation of
 Pennsylvania

Application February 6, 1934, Serial No. 709,979
 Renewed February 25, 1939

14 Claims. (Cl. 24—205)

The present invention is designed to improve separable fasteners of the slide type. The more common manner of securing the interlocking members of separable fasteners to the stringers, or tapes, is to clamp jaws formed on the members over a beaded edge on the stringer. In the present invention the interlocking members are formed with heads having comparatively thin shanks extending from them and these shanks 10 are secured preferably by surface union with the stringers. In order that the attachment of the members may be made more secure the stringers are preferably provided at the edge to which the members are secured with opposing 15 lips which extend each side of and embrace opposing faces of the shanks. Preferably also these lips are crowded together between the members so that the opposing lips themselves are secured together. In carrying forward this feature the lips 20 are preferably faced with a filler which more certainly fills the space between the members. The stringers are also preferably re-enforced at the base of the lips.

A further feature of the invention is directed 25 to the special shapes of the interlocking members and stops.

Features and details of the invention will appear from the specification and claims.

A preferred embodiment of the invention is 30 illustrated in the accompanying drawings as follows:

Figs. 1 to 12 show end views of different modifications of stringers.

Fig. 13 shows a view of an interlocking member from the projection face.

Fig. 14 an elevation of the member showing the side face of the projection.

Fig. 15 a view of the recessed side of the interlocking member.

Fig. 16 an end view of the interlocking member.

Fig. 17 a perspective view of the stop at the closed end of the fastener.

Fig. 18 a modified stop for the closed end.

Fig. 19 a perspective view of a stop for the open ends of the fastener.

Fig. 20 an elevation of a fastener, a part of the slide being in section.

Fig. 30 a modification of stop for the closed end.

Fig. 31 a perspective view of a modified stop for the open end of the fastener.

1, as shown in Fig. 20, marks the stringers and 2 the interlocking members. These members are each provided with a head 3 and a comparatively thin shank 4 extending therefrom. The heads have recesses 5 on one face and projections 6 on the opposite face, this relation being the common relation in separable fasteners of this type. The shanks 4 extend between lips 1a which are arranged in the modification shown in Fig. 22 as branches of the stringer 1 along 20 the securing edge. This tape is thickened on the inner faces of the lips which forms a filler 1b. This filler through the compression of the filler and lip on the shanks is forced largely into the space between the shanks so as to bring the filler 25 portions of the lips into contact closing the opening between the lips and preferably securing one lip to the other through the engagement and union of the fillers. The shanks of the members are secured to the stringers by a suitable 30 cement which forms a surface union between the faces of the shanks and stringers. If formed of Celluloid, or similar material the cementing material may be supplied by a suitable solvent carried by the tape itself which operating on the 35 Celluloid dissolves a sufficient part of the engaged surface to form the cement so that when it hardens it makes a firm union with the tape. The extended surfaces of these shanks assure a more definite union than devices having less 40 surface engaged. The member also lends itself readily to fabrication and gives to the member greater strength than some shapes where the securing ends, for instance, are divided.

A slide 7 is formed of side plates each having 45 guide channels 1a. These are the usual Y form and the plates are secured together by the connecting post 7b. The usual pull tab 8 is secured to the slide so that it may be readily operated. The fastener as a whole operates in the manner 50 common to separable fasteners of the slide type. As the slide is moved along, the members are fanned out and swing into interlocking position and as the slide passes over them they assume a position in parallel extending from the opposing 55

stringers with the opposing recesses and projections in engagement. The bottom stop, or stop for the closed end of the fastener 9 is provided with an enlargement at the center which will readily engage the slide and has oppositely extending shanks 9a which extend between the lips in the edges of the opposing stringers. Upper stops 10 have shanks 10a and the shanks 10a extend within the lips and are secured in the same manner as are the interlocking members.

Various modifications of stringers are shown. The one shown in Figs. 21 and 22 has already been described.

15 In Fig. 1 the stringers are formed in two plies 11 connected by a loop 11a. Securing edges, or lips of the stringers are provided with fillers 11b which are fabricated with the plies 11.

20 The modification shown in Fig. 2 has two separate plies 12, each of which is supplied with a filler 13 at the securing edge. In this structure the plies are closed when the stringer is secured to the article with which it is used.

25 In Fig. 3 the structure illustrated is similar to that shown in Figs. 20 to 22. The stringer here has a single ply 14 with branches 14a and filler 14b fabricated with the branches.

30 Fig. 4 indicates a stringer having plies 16, the two plies being secured together by fabrication at 17 and the extension of the plies at 16a forming the securing lips.

35 Fig. 5 has a somewhat similar stringer having two plies 18 secured by a cord 19 fabricated with the stringer and has the extending securing lips 18a.

40 The modification of Fig. 6 shows the stringer formed in two plies 20 connected by a loop 21. A cord 22 is also arranged between the plies at the base of the lips 20a and this cord is secured in place by a stitching 22a.

45 In the modification shown in Fig. 7 the stringer is formed of two plies 23 connected by a loop 23a. The securing edge of the stringer 23b is supplied with a filler 24 and this filler is secured to the plies 23 by rows of stitching 24a.

50 In the modification shown in Fig. 8 there is a stringer with a single ply 25, branches 25a forming the securing lips. Fillers 26 are secured to the inner faces of the lips by rows of stitching 26a.

55 The modification of Fig. 9 shows a single ply stringer 27 with lips formed by branches 27a. The stringers are reenforced at the crotch by a cord 28 which is secured in place by a stitching 28a.

60 In the modification shown in Fig. 10 the stringer is formed of a single ply 29 with the branch lips 29a and has a re-enforcement 30 which is formed in the crotch of the branches during fabrication.

65 In the modification shown in Fig. 11 a single ply stringer 31 is used with branch lips 31a and the stringer is re-enforced at the base of the lips by cords 32 which are secured on opposite faces of the stringer by stitching 32a.

70 In the structure of Fig. 12 the stringer is formed of a single ply 33 with branch lips 33a and a re-enforcement 34 at the base of the lips, said re-enforcement being fabricated with the stringer.

75 Any of these stringers may be used in the manner of the stringer shown in Figs. 20 to 22 and secured to the shanks of the members in the same manner.

Figs. 13, 14, 15 and 16 show different views of

the interlocking members 2 heretofore described in connection with Figs. 20 to 22 and Figs. 17 and 19 illustrate the stops heretofore described in relation to Fig. 20.

5 In Fig. 17 a modified stop is shown which has a head 35 with shanks 35a extending in each direction. The head 35 is arranged only at one edge of the stop and thus permits the end of the slider to pass over a portion of the stop before engaging the shoulder.

10 In Figs. 23 to 25 a modified form is shown in which the stringers 26 are of single ply, but provided with a filler 36a along their securing edges. Interlocking members are provided with heads 37 and shanks 38. The shanks are preferably off-set from the centers of the heads so that the stringer will occupy a position approximately at the center of the head. The heads are provided with recesses 39 and projections 40. The stringers are secured by surface unions with 20 the single faces of the shanks, as clearly shown in Fig. 24. The pressure with which this union is accomplished preferably forces the filler into the space between the members. A slide 41 operates on the heads 37, these slides being provided with channels 42 which engage the head and the sides of the slider are connected in the usual manner (not shown).

25 Stops 43 for the closed end of the fastener are provided. These are provided with shanks 43a 30 extending over the securing edge of each stringer and are secured thereto in the same manner as the interlocking members. The shanks on the stop are off-set in a manner similar to the off-setting of the shanks on the members. Stops for 35 the open ends of the fastener have heads 44 with shanks 44a extending over the surface of the stringers and are secured thereto in the manner of the shanks of the other members and the shanks are similarly off-set with relation to 40 the head.

40 In the modification shown in Fig. 29 the members have heads 45 from which shanks 45a extend. Here the shank is flush with one edge of the head and consequently permits of the use 45 of a slide having a single channel plate. The heads have the usual recesses and projections 46 and 47. A stop 48 with oppositely extending shanks 48a is used with the member shown in Fig. 29, the shanks being flush with one edge 50 of the stop and the stop 49 is provided for the open end of the fastener using the members shown in Fig. 29 and has a shank 49a flush with one edge of the stop.

55 It will be noted that the shanks may be made comparatively thin and consequently the total thickness of the fastener may be comparatively thin, the only feature requiring some definite dimension being the recesses and projections.

60 What I claim as new is:

1. A separable fastener comprising opposing series of interlocking members and a pair of stringers for the members having lipped edges, said lips embracing and securing portions of the interlocking members between them, at least one 65 of the lips being thickened on its inner face to provide a filler between the members.

2. A separable fastener comprising opposing series of interlocking members and a pair of stringers for the members having lipped edges, 70 said lips embracing and securing portions of the interlocking members between them, at least one of the lips being thickened at its inner face to provide a filler between the members, the lips being secured together between the members.

3. A separable fastener comprising opposing series of interlocking members; a pair of stringers for the members each having Y-shaped lipped edges, said lips embracing and securing portions 5 of the interlocking members between them; stops formed with shanks embraced by the lips; and a slider operating on the fastener engaged by the stops.

4. A separable fastener comprising interlocking members; stringers for the members each having lipped edges, said lips on each stringer embracing and securing portions of the interlocking members between them; a stop for the fastener having a head and a shank extending into one of the 10 stringers, said shank being embraced by and secured to the lips; and a slider operating on the members and engaging said stop.

5. A stringer for separable fasteners having lipped securing edges, said stringer having a re-enforcement fabricated with the fabrication of 20 the stringer along the base of the lips, and interlocking members secured between the lips.

6. A stringer for separable fasteners having lipped securing edges, said stringer having a re-enforcement fabricated with the fabrication of 25 the stringer and within and along the base of the lips; and interlocking members secured between the lips.

7. A stringer for separable fasteners having lipped securing edges, said stringer having a re-enforcement fabricated with the fabrication of the stringer and on the outer face of the stringer 30 and at the base of the lips; and interlocking members secured between the lips.

8. A stringer for separable fasteners comprising a single ply terminating in branches along one edge of the member forming securing lips, said stringer having a re-enforcement at the 35 crotch formed by the branches; and interlocking members secured between the lips.

9. A stringer for separable fasteners having lipped securing edges, said stringer having a re-enforcing cord permanently fabricated into the stringer along the base of the lips; and interlocking members secured between the lips.

10. A stringer for separable fasteners comprising a single ply terminating in branches along one edge of the member forming securing lips, said stringer having a re-enforcing cord permanently fabricated into the stringer along the 10 crotch formed by the branches.

11. A stringer for separable fasteners having lipped securing edges, one of said lips at least being thickened to provide a filler on its inner 15 face; and interlocking members secured between the lips.

12. A stringer for separable fasteners having lipped securing edges, one of the lips at least being provided with a filler on its inner face fabricated with the stringer; and interlocking mem- 20 bers secured between the lips.

13. A stringer for separable fasteners having lipped securing edges, one of the lips at least being thickened to provide a filler on its inner face 25 secured to the stringer; and interlocking mem- bers secured between the lips.

14. In a separable fastener of the class described having a pair of flexible stringers, cooperating series of interlocking members arranged on adjacent edges of the stringers, and a slider movable along said stringers for opening and closing the fastener, a stop member for the slider arranged at one end of the series of interlocking members and having a head portion intermediate 30 its ends and shanks of thinner cross-section than the head portion, said shanks being secured to the opposite flexible stringers.

NOEL JOSEPH POUX.
